UNITED STATES PATENT OFFICE

131,487

DESIGN FOR AN ADVERTISING DEVICE

Wilbur B. Cope, Washington, D. C.

Application July 10, 1941, Serial No. 102,014

Term of patent 3½ years

To all whom it may concern:

Be it known that I, Wilbur B. Cope, a citizen of the United States of America, residing in the city of Washington, District of Columbia, have invented a new, original, and ornamental Design for an Advertising Device, of which the following is a specification, reference being had to the accompanying drawing, forming part thereof.

I claim:

The ornamental design for an advertising device, substantially as shown.

WILBUR B. COPE.
